COLOR SELECTOR

Irwin C. Bowman, Glenview, Ill.

Application August 23, 1955, Serial No. 529,971

1 Claim. (Cl. 35—28.3)

The invention relates to color selectors or comparators for displaying a wide range and gradations of color-combinations for visual comparison in selecting combinations of colors, tints and shades.

One object of the invention is to provide a color selector or comparator which includes a single chart with a wide range of colored panels, and a series of interchangeable masks with windows for displaying color combinations according to varying color schemes or laws.

Another object of the invention is to provide a color selector which comprises a chart of colors and a series of masks which are interchangeable and reversible on the chart for displaying a wide range of different combinations of colors.

Other objects will appear from the detail description.

The invention consists in the several novel features which are hereinafter set forth and are more particularly defined by claims at the conclusion hereof.

In the drawings:

Fig. 1 is a plan view of a base having a color chart thereon in accordance with the invention;

Fig. 2 is a section taken on line 2—2 of Fig. 1, with a mask on the base;

Fig. 3 is a plan view of the color chart and a mask having windows for selecting complementary colors;

Fig. 4 is a similar view with a mask having windows for selecting a triad of colors;

Fig. 5 is a similar view with a mask with windows for selecting split complementary colors;

Fig. 6 is a similar view with a mask for selecting a complement of near colors;

Fig. 7 is a similar view with a mask having windows for selecting another complement of near colors;

Fig. 8 is a similar view with a mask having windows for displaying analogous colors; and

Fig. 9 is a similar view with a mask having windows for selecting a combination of colors of the same family.

The invention includes generally a base or back 11 of any suitable material which is provided on its top face with a chart of colors and comprises an annular series of segmental zones, each including a radial series of panels of colors, tints, shades, and a series of masks which fit over, are adapted to be interchangeably placed on the chart, and provided with differentially located windows for exposing different combinations of colors, tints and shades in predetermined panels of different zones on the chart.

The chart exemplifying the invention is of polygonal contour, for example, hexagonal, and is divided by radial lines 15 and 16 into an annular series of twelve segmental zones. The lines 15 extend inwardly from the corners between the polygonal sides of the chart and the lines 16 extend inwardly from the centers of said sides to provide zones which are substantially of the contour of a right-angled 60°—30° triangle. The lines 15 and 16 are alternated circumferentially to dispose the contiguous zones in pairs with lines 15 forming the abutting right-angled radial sides between one pair of contiguous zones

2

and lines 15 forming the contiguous acute-angled sides between alternate pair of abutting zones. This makes it possible by reversal of the faces of the masks on the chart as hereinafter described to spot the windows in the masks to expose panels in either of the zones of each pair on opposite sides of line 16.

The 30° segmental zones of the chart are designated 21, 22, 23, 24, 25, 26, 27, 28, 29, 30, 31 and 32, respectively. Each of said zones is provided with a radial series of trapezoidal panels *a*, *b*, *c*, *d*, *e* and *f*, which have circumferential or inner and outer sides parallel with sides 17 of the chart and extend circumferentially between adjacent radial lines 15 and 16.

Each series of panels may be used to display a family 15 or related group of different colors and their derivatives or gradations or several zones may be used for groups of similar colors with different gradations or for split basic colors and gradations. These panels are differentially exposed by the windows in the masks for displaying 20 different color-combinations from the chart according to the different locations of the windows on the charts and the positions of the masks on the chart. The masks include, for example, a series of seven masks designated 40, 41, 42, 43, 44, 45 and 46, respectively, these masks 25 being hexagonal in contour conforming substantially to the hexagonal contour of the chart. A hexagonal rib 12 on the base 11 conforms to the sides of the mask and the base and exemplifies means on the base adapted to spot each mask in annular symmetrical positions 60° apart 30 on the base 11 for predetermined positions of the windows in the mask in relation to the panels in the segmental zones of the color chart.

The masks are provided with windows of trapezoidal contour conforming to series of panels which are to be 35 selectively exposed, and are positioned to overlie panels which have corresponding radial positions in the segmental zones when the masks are disposed in symmetrical annular positions around the chart. Each mask fits within the rib 12 in six annular positions on the chart 40 so that each window is adapted to register with or expose corresponding radial panels in each of six or alternate zones of the color chart and when its face is reversed and its opposite face is on the chart, the windows will be disposed to display panels in the other six alternate zones 45 of the chart. Preferably both faces of the charts are black or dark in color for contrast with the displayed colors on the chart.

The zones on the chart have numerical designations 13 for identifying their positions relatively to the masks in 50 their selectively annular positions on the zones of the chart. For example, the mask 40 has three windows for exposing panels *f*, *d* and *b* of three colors in one zone of the chart and windows for simultaneously exposing panels *a* and *d* in a diametrically opposite zone of the chart. Mask 41 has windows for simultaneously exposing panels *f*, *c* and *b* in one zone, a panel *d* and a panel *e* in two different zones of the chart. Mask 42 has windows for simultaneously exposing panels *f*, *d* and *b* in one zone and panels *d* in two other zones. Mask 43 55 has windows for exposing panels *e*, *c* and *a* in one zone and panels *b* and *e* in a nearly opposite zone of the chart. Mask 44 has openings for exposing panels *e*, *c* and *a* in one zone and panels *e* and *b* in an angularly opposite zone of the chart. Mask 45 has windows for exposing panels *a*, *b* and *d* in one zone and panels *e* and *f* in adjacent zones. Mask 46 has windows for simultaneously exposing the entire series of panels in a single zone.

Each mask, being separable from and interchangeable on the chart, can be spotted in six annularly disposed symmetrical positions 60° apart on the chart and when the face of the mask is reversed on the chart, can be

spotted into six annularly disposed alternate zones. The placement of the masks in said predetermined positions is facilitated by registry of the conforming edges of the masks with the inner sides of rib 12 on the base 11 which functions as means for spotting the masks circumferentially and radially on the chart.

The colors displayed on the chart follow the colors of the spectrum, and by way of example, the zones may include a group of tints, shades and tones of the following colors, viz: zone 21, red; zone 22, red orange; zone 23, orange; zone 24, yellow orange; zone 25, yellow; zone 26, yellow green; zone 27, green; zone 28, blue green; zone 29, blue; zone 30, blue purple; zone 31, purple; zone 32, red purple. These color-panels lend themselves for the selection of a wide range of combinations of complementary colors; analogous colors; and monotone colors.

The selector will be used as follows: When the mask 40 is placed on the chart as shown in Fig. 3 with the examples of colors described, the windows in said mask will expose or display three red tones or colors on panels *f*, *d* and *b* in zone 21 and two green tones in panels *a* and *d* of zone 27.

Complementary colors from the different groups or families of color in zones 23, 25, 27, 29 and 31 may be displayed in combination by spotting mask 40 so its windows will overlie and expose panels *f*, *d* and *b* in said zones respectively, and simultaneously expose the panels *a* and *d* in zones 29, 31, 21, 23 and 25, respectively. In this manner said mask can be selectively placed on the chart to display six different combinations of color on the panels of the chart. The mask 40 when reversed on the chart to impose its opposite face on the chart as indicated by dotted lines in Fig. 3, will position the windows to expose three tones of orange on panels *f*, *d* and *b* in zone 23 and two zones of blue-green on panels *a* and *d* in zone 28. While reversed, mask 40 may be selectively placed to expose panels *f*, *d* and *b* in zones 24, 26, 28, 30 and 32 and panels *a* and *d* in zones 28, 30, 32, 22 and 24 respectively, for displaying other or different complementary color combinations from the other six zones of the chart.

When mask 41 is imposed on the chart as shown in Fig. 4, the windows will simultaneously expose three tones of red on panels *f*, *c* and *b* in zone 21, one tone of yellow on panel *d* in zone 25 and a tone of blue on panel *e* in zone 29. Other triad combinations may be displayed by placement of said mask so its windows will simultaneously expose panels *f*, *c* and *b* in zones 23, 25, 27, 29, and 31 respectively, panel *d* in zones 27, 29, 31, 21 and 23, and panel *e* in zones 27, 29, 31, 21 and 23 respectively. When mask 41 is reversed on the face of the chart, as indicated by dotted lines in Fig. 4, the windows will simultaneously expose three tones of red-orange on panels *f*, *c* and *b* of zone 22, one tone of yellow-green on panel *e* in zone 26 and one tone of blue-purple on panel *d* in zone 30. With said mask so reversed the mask may also be spotted so its windows will simultaneously expose three panels *f*, *c* and *b* in zones 24, 26, 28, 30 and 32, and panel *e* in zones 28, 30, 32, 22 and 24 for different triad combinations of color.

When the mask 42 is imposed on the chart as shown in Fig. 5, the windows in said mask will expose three tones of red on panels *f*, *d* and *b* in zone 21, a panel *d* of yellow-green in zone 26 and panel *d* of blue-green in zone 28 for visual selection of split complementary colors from said zones. Similar exposures of three color combinations from different groups or families of color on the chart may be made by spotting its windows to simultaneously overlie and expose panels *f*, *c* and *b* in zones 23, 25, 27, 29 and 31, panel *d* in zones 28, 30, 32, 22 and 24, panel *d* in zones 30, 32, 22, 24 and 26, respectively. In this manner mask 42 will selectively display six different three-color combinations from the zones on the

chart. When mask 42 is reversed on the chart to superpose its opposite face on the chart as indicated by dotted lines in Fig. 5, the windows will be positioned to expose panels *f*, *d* and *b* of red-orange in zone 22, panel *d* of green in zone 27 and panel *d* of blue in zone 29 to display different three-color combinations. Three tones of red, one tone of green and one tone of blue will then be displayed. When the faces of said mask are reversed, the mask may also be placed on the chart so its windows will simultaneously expose panels *f*, *d* and *b* in zones 24, 26, 28, 30 and 32, panel *d* in zones 29, 31, 21, 23 and 25 respectively and panel *d* in zones 31, 21, 23, 25 and 27 respectively, for displaying different split complementary color combinations in the group of said zones. In this manner mask 42 will display color combinations from the other six zones of the chart.

When mask 43 is imposed on the chart as shown in Fig. 6, the windows in said mask will expose panels *a*, *c* and *e* of red-orange in zone 22 and panels *e* and *c* of blue in zone 27 for visual selection of near complementary colors from said zones. Exposures of other near complementary color combinations from the different groups or families of color in the zones may be made by spotting mask 43 so its windows will overlie and expose panels *a*, *c* and *e* in zones 24, 26, 28, 30 and 32, and panels *e* and *b* in zones 29, 31, 21, 23 and 25 respectively. In this manner mask 43 will selectively display six different combinations of color. Mask 43 when reversed on the chart to impose its opposite face on the chart as indicated by dotted lines in Fig. 6 will expose panels *a*, *c*, and *e* of red in zone 21 on panels *e* and *b* of blue-green in zone 28 of the chart for different complementary color combinations. With the faces of the mask so reversed, the mask may also be placed on the chart so its windows will simultaneously expose panels *a*, *c* and *e* in zones 23, 25, 27, 29 and 31, and panels *e* and *b* in zones 30, 32, 22, 24 and 26, respectively, for displaying different complementary color combinations from the group in said zones.

When mask 44 is imposed on the chart as shown in Fig. 7, the windows in said mask will expose in combination three tones of red-orange panels *e*, *c* and *a* in zone 22, and two tones of blue on panels *e* and *b* in zone 29. Other complementary combinations may be displayed by placement of said mask so its windows will simultaneously expose panels *e*, *c* and *a* in zones 24, 26, 28, 30 and 32, and panels *e* and *b* in zones 31, 21, 23, 27 and 29 respectively. When mask 44 is reversed on the face of the chart, as indicated by dotted lines in Fig. 7, the windows will simultaneously expose three tones of red on panels *e*, *c* and *a* in zone 21, and two tones of blue on panels *e* and *b* in zone 26. With said mask so reversed the mask 44 may also be spotted so its windows will simultaneously expose three panels *e*, *c* and *a* in zones 23, 25, 27, 29 and 31, and panels *e* and *b* in zones 28, 30, 32, 22 and 24, respectively, for different combinations of complementary colors.

When mask 45 is imposed on the chart as shown in Fig. 9, the windows in said mask will expose in combination three tones of red-orange on panels *a*, *b* and *d* in zone 22, a tone of red-orange on panel *e* in zone 21 and a tint of orange on panel *f* in zone 32. Other combinations may be displayed by placement of said mask so its windows will simultaneously expose panels *a*, *b* and *d* in zones 24, 26, 28, 30 and 31, panel *e* in zones 23, 25, 27, 29 and 31, and panel *f* in zones 22, 24, 26, 28 and 30 respectively. When mask 45 is reversed on the face of the chart, as indicated by dotted lines in Fig. 8, the windows will simultaneously expose three tones of red-orange on panels *a*, *b* and *d* of zone 21, a different tone of red on panel *e* in zone 22 and one tone of orange on panel *f* in zone 23. With said mask so reversed it may also be spotted so its windows will simultaneously expose three panels *a*, *b* and *d* in zones 23, 25, 27, 29 and 31, panel *e* in zones 24, 26, 28, 30 and 32, and a

panel *f* in zones 25, 27, 29, 31 and 21 respectively, for different combinations of complemental colors.

When mask 46 is imposed on the chart as shown in Fig. 9, the windows in said mask will expose all the tones or gradations of red on the entire series of panels in zone 21. Other colors on the panels in a radial series may be displayed by placement of said mask so its windows will simultaneously expose the panels in zones 23, 25, 27, 29 and 31 respectively. When mask 46 is reversed on the face of the chart, as indicated by dotted lines in Fig. 9, the windows will simultaneously expose the series of panels of red-orange in zone 22. With said mask so reversed, the mark may also be spotted so its windows will simultaneously expose the series of panels in zones 24, 26, 28, 30 and 32, respectively for different combinations of monotone colors.

The invention is not to be understood as restricted to the details set forth since these may be modified within the scope of the appended claims without departing from the spirit and scope of the invention.

Having thus described the invention what I claim as new and desire to secure by Letters Patent is:

A color selector for displaying selected colors in harmonious combinations, said selector comprising a flat sheet-like base member of hexagonal equi-lateral equi-angular configuration, said base member bearing on one face thereof a field of colors, said field being divided into twelve contiguous segments, each segment being in the form of a right angle triangle the hypotenuse of which extends radially from the exact center of the 30 hexagonal base member to the juncture between a pair of adjacent hexagon sides, each segment being divided into a series of at least four stripes of equal width with each stripe extending parallel to the peripheral hexagon edge which forms one boundary of the segment, the stripes of each segment being of equal width, the stripes of three pairs of adjacent segments extending in end-to-

end axial alignment in respective pairs, the stripes of three other pairs of adjacent segments extending in end-to-end relationship in respective pairs at angles of 120° each, each stripe thus being in the form of a trapezoid of the 90°, 90°, 60°, 120° variety, the stripes of each segment presenting different gradations of a base solar spectrum color, the base color thus represented by each segment being different from the base color represented by each other segment, said one face of said base member being provided with a hexagonal rib in the peripheral regions thereof enclosing and closely bounding said field of colors, and a plurality of masks adapted to overlie said field of colors interchangeably, said masks each being of hexagonal configuration and conformable in size to the size of said field of colors so that when the masks are in position over said field of colors individually, they are releasably retained in position by said hexagonal rib, each mask being formed with a plurality of window openings therethrough with each opening conforming in 20 shape to the shape of a stripe on the base member with which the opening is adapted to register when the mask is in operative position within the confines of said rib with either face of the mask in contact with said base member, the positional arrangement of the window openings of the various masks differing from one another, each window opening, when in register with a given stripe, exposing substantially the entire area of the stripe.
